J. C. KENNEDY.

Cooking Stove.

No. 11,295.

Patented July 11, 1854.

UNITED STATES PATENT OFFICE.

JAMES C. KENNEDY, OF ALBANY, NEW YORK.

ELEVATED OVEN.

Specification of Letters Patent No. 11,295, dated July 11, 1854.

To all whom it may concern:

Be it known that I, JAMES C. KENNEDY, of the city of Albany and State of New York, have invented certain Improvements 5 in the Construction of the Elevated Oven Used with Cooking-Stoves; and I declare the following specification, with the drawings hereto attached as part of the same, to be a full and perfect description thereof.

10 Figure 1 represents a perspective view of a cooking stove with the elevated oven attached. Fig. 2 represents a front view of the oven, the front plate, and the top plate being removed to show the interior construction and arrangement of the flues.

Similar letters in both figures refer to the same parts of the ovens.

The letters S, S, S, S show the stove and A, A, A, A, the oven. It is well known that 20 in the usual construction of elevated ovens the heat, smoke, &c., from the furnace pass between the shell or outer plates of the oven around the front and rear of the oven proper, and meet over its top, where they 25 pass off through the smoke pipe; the oven doors being situated at each end of the structure.

My proposed improvement consists in placing within the shell or outward plates 30 A A A A two distinct ovens X X, whose doors B, B, shall open through the back, or front plates or through both, the ovens being so placed as to leave flues C, D, one at each end of the shell between it and one of 35 the ovens also a space or flue E I between the ovens and a space or flue H between the top of the oven and the top plate T of the shell, the top plate being made in the usual form with a flue or pipe P issuing from it.

40 The flue C is governed by a damper J and flue D by a damper K and flue H by a damper L—these dampers being the usual

slide plate dampers, as ordinarily fitted for stove flues. Three ovens or more may be arranged in a similar manner in stoves of 45 very large size, in each case with a flue with its regulating damper between each oven, operating in a manner similar to the two ovens described.

The arrangement of the three flues with 50 their regulating dampers, permitting the person using the stove to direct the flame and heat around both ovens simultaneously, or around one alone, or through the center flue directly, enables the cook to give an equable 55 heat to both the ovens when required, placing this apparatus upon the same footing with the ordinary oven, or to give a greater degree of heat to one oven than to the other when articles to be cooked at the same time 60 require different temperatures, which cannot be done with the ordinary oven, or when the oven is not needed to send the hot air and gases directly through the center flue into the chimney, thus saving the plates of the 65 ovens from the effects of the fire, whereas in the common oven the flame, &c., always passes around and heats and wears out its plates, whether needed for cooking or not.

I claim—

The combination of two or more ovens in the elevated oven chamber or shell with flues for hot air between each end of the chamber and one of the ovens, also with a flue between each oven, all the flues being 75 provided with regulating dampers for the proper management of said oven and flues, substantially as the same is set forth and described in the above specification.

JAS. C. KENNEDY.
